UNITED STATES PATENT OFFICE.

ALBERT HERBERT SMITH, OF GREAT FALLS, MONTANA.

FLYING-MACHINE.

1,200,251.

Specification of Letters Patent.

Patented Oct. 3, 1916.

Application filed November 27, 1915. Serial No. 63,732.

To all whom it may concern:

Be it known that I, ALBERT HERBERT SMITH, a citizen of the United States, and a resident of Great Falls, in the county of 5 Cascade and State of Montana, have invented a certain new and useful Improvement in Flying-Machines, of which the following is a specification.

My invention is an improved aerial navigating machine of the heavier-than-air type 10 and consists in the constructions, arrangements and combinations of parts herein-after described and claimed.

The principal object of my invention is 15 to provide a machine of the class described in which all stresses to which it may ordinarily be subjected are transmitted to the framing which is constructed and braced in such a manner that the strains imposed 20 on it, must equal the crushing strength of the material from which the frame is made, before it will collapse.

Another object of the invention is the 25 provision of devices for maintaining and restoring the equilibrium of the machine, these devices being comparatively simple of construction and consequently easy of operation.

Other objects and advantages will appear 30 in the following description, reference being had to the accompanying drawings in which:—

Figure 1 is a perspective view of the machine as in flight. Fig. 2 is a detail perspective view partly in section, of the horizontal 35 stabilizing plane universal joint. Fig. 3 is a perspective view of the machine as viewed from another point. Fig. 4 is a detail perspective view of a part of the main plane 40 showing the covering partly removed from the ribs. Fig. 5 is a perspective view of the drums and pulleys. Figs. 6 and 7 are diagrammatic views hereinafter referred to. Figs. 8 and 9 are diagrammatic views of 45 other parts of the machine to be herein-after referred to.

In the drawings, 1 is the main mast which as will be seen from Figs. 1 and 3, is disposed vertically. The mast 1 supports 50 a horizontally and longitudinally disposed beam 2 at a place approximately two-thirds of the height of the mast 1; the beam 2 is secured to the mast 1 at a place about two-thirds of its length so that the short forwardly extending portion forms a brace 55

support and the longer rearwardly extending portion forms a support for the rudders, etc. which will be described.

Slightly above the connection of the mast 1 and beam 2 and secured to the mast 1 in 60 any suitable manner as indicated in Fig. 4 is the main lateral beam 3 of the main supporting plane which is generally indicated by 4. The main plane 4 is composed of a suitable number of ribs 5 which are covered with a suitable weather-proof fabric 6, the fabric being drawn over both the top and bottom of the ribs as shown in the drawings. The main plane 4 is set at an angle 65 of incidence of approximately three to six degrees this being done to cause the proper reaction to sustain the machine in the air when in flight.

Mounted below the main plane 4 and in 70 parallelism therewith is an auxiliary sustaining plane 7 which is substantially "diamond" shaped in form as shown in Fig. 1. The plane 7 is mounted on wires or ropes 75 stretched between certain ones of the brace wires of the framing, and may be formed 80 by ribs similar to those in the main plane 4.

The frame of the machine which consists principally of the mast 1, and the longitudinal and transverse beams 2 and 3, respectively, is braced by wires, the principal ones 85 of these being secured to an anchor 8 located at the foremost end of the longitudinal beam 2. Brace wires 9 and 10 extend from the anchor 8 to the extremities of the transverse beam 3 where a common connection 90 is made to other brace wires 11 and 12 which extend from this place to the tip of the main mast 1 as shown in Fig. 1. Other wires 13 and 14 are connected between the lower end of the mast 1 and the common 95 connection at the extremities of the beam 3; wires 15 and 16 extend rearwardly from these latter connections and are secured near the rear end of the beam 2 as shown in Fig. 1. Other points on the anchor 8 serve to 100 hold other brace wires 17 and 18 which extend to the top and bottom ends of the mast 1; from thence the wires 19 and 20 extend rearwardly and are connected to the beam 2 near the rear end thereof.

A cable 21 stretched between the wires 13 and 14 as shown in dotted lines in Fig. 1 forms the basis of the auxiliary plane 7 the bounding edge of which is formed by the cable 22 which is secured with the cable 21 110

to the wires 13 and 14. The cable 22 is held in shape and place by additional brace wires 23 and 24.

When on the ground, the machine rests 5 on the wheels 25 which are mounted on a cross bar on the lower end of the mast 1, suitable braces being provided to preserve the rigidity of the cross bar. A skid 26 is secured to the rear end of the beam 2 as 10 shown and serves to hold the machine in the proper attitude for rising into the air.

The rectifying plane 27 consists of fabric drawn over the upper portion of the converging brace wires 17 and 19 as shown in 15 Fig. 1. The purpose of the plane 27 is to intercept any lateral air current which might destroy the equilibrium of the machine; when the force of the air is exerted against the plane 27, the machine is caused 20 to tilt to one side at which time certain devices hereinafter to be described, are brought into action and restore the balance of the machine.

Mounted on a bar 28 arranged parallel to 25 the main plane 4 and just below the rectifying plane 27, is a stabilizing plane 30. The bar 28 of the plane 30 is rotatably mounted in the bore of the universal joint 29 which is located in the interior of the mast 1. The 30 universal joint 29 is provided with trunnions 31 at opposite sides; these trunnions rest in suitable bearings in the body of the mast 1, as shown. The plane 30 is formed by ribs 32, as shown in Fig. 2, over which 35 the fabric is drawn. The universal joint 29 permits the plane 30 to be tilted longitudinally or laterally as the occasion may require.

The stabilizing plane 30 is tilted by means 40 of a pair of sheaves 33 and 34 which are mounted on a shaft 35 and supported by a bracket 36^a from the mast 1 as shown in Fig. 5. Each one of the sheaves is independently operable by a lever 36 and 37. 45 The levers and sheaves are located within convenient reach of the aviator on the seat 38 the seat being suitably suspended and braced as shown.

A cable 39 is wound once or twice around 50 the sheave 33 and from thence each part of the cable extends over suitably located guide pulleys 40-40^a and 41-41^a upwardly through the main plane 4; the parts of the cable then take over other guide pulleys 55 42-42^a and the ends of the cable parts are secured fore and aft of the plane 30. The rotation of the sheave 33 causes the longitudinal tilting of the plane 30. Similarly, a cable 43 winds over the sheave 34 from 60 whence the parts thereof are guided over pulleys 44-44^a and 45-45^a to other guide pulleys 46-46^a and then are secured laterally of the plane 30. The rotation of the sheave 34 causes the plane 30 to be tilted 65 laterally.

A shaft 47 is located below the seat 38 and a pair of treadles 48 and 49 are supported on this shaft as shown in Fig. 9. Each one of the treadles is secured to a sleeve which is rotatably mounted on the 70 shaft 47 and permits the independent rocking of the treadles thereon. Arms 52 and 53 are secured to the sleeves of the respective treadles 48 and 49 and cables 54 and 55 are secured to the respective arms as shown 75 from whence the cables 54 and 55 extend rearwardly and are secured to the rudder moving arms. The cable 54 is secured to the arm 56 of the horizontal rudder 57 while the cable 55 is secured to the arm 58 of the 80 vertical rudder 59 both of the rudders being suitably mounted on the framing of the machine. The aviator can shift either rudder 57 or 59 by rotating either treadle 48 or 49.

Either side of the planes 4 and 7 may simultaneously be warped for banking the machine when making a turn by the application of the aviator's weight against one or the other side of the shiftable chair arms 90 60-60^a. A cable 61 is secured to the front edges of the planes 4 and 7 at one side as shown in Fig. 6 and passes over a guide pulley 62 which is supported by the brace wire 11; from thence the cable 61 passes 95 over another pulley 63 located at the top of the mast 1 and then downwardly and over a pulley 64 to the arm 60^a of the seat. A similar cable 65 is secured to the opposite front edges of the planes 4 and 7 and passes over 100 pulleys 66, 67, 68, and 69 and is fastened to the other arm 60 of the seat. When the aviator applies his weight against either one of the chair arms, the corresponding side of the planes 4 and 7 are warped by means of 105 the cables just described.

The rear edges of the planes 4 and 7 are connected by cables 66 and 67 as shown in Fig. 3, springs 66^a and 67^a being interposed so that a resilient connection is afforded the 110 planes when warped, the springs also serving to assist in returning the planes to their normal position when the aviator releases the pressure. Other cables 68 and 69 are connected between the rear edges of the 115 plane 4 and the brace wires 11 and 12 suitable springs 68^a and 69^a being interposed in the cables as shown. The engine 70 is supported on the frame of the machine in any suitable manner and may be of any approved 120 design. The propellers 71 and 72 are driven by the engine through the chains as shown in Fig. 3.

Having thus described the construction of the machine, the method of its operation is 125 as follows: By reference to Fig. 6 it will be seen that the machine has been tilted to one side by the force of a gust of wind against the top plane 27. This tilting of the machine naturally disturbs the center of grav- 130

ity of the machine, tending to throw it upwardly toward the raised side. The aviator's weight now falls against the lower arm 60 of the seat and a pulling force is exerted through the cable 61 on the front edges of the planes 4 and 7 which are by this means warped as shown in Fig. 7. The warping of these planes increases the angle of incidence of the lifting surfaces of the two planes against the air and the machine is in consequence again righted. If the rudders are found necessary to augment the balance restoring function of the planes as just described, the aviator can readily manipulate either treadle 48 or 49 as the occasion may dictate. In making a turn while in mid-air, the aviator must shift his weight toward that side on which the planes 4 and 7 are to be warped so that the centrifugal action on the machine and the consequent disturbing of the center of gravity be counteracted by banking the machine against the air on the opposite side against which the turn is to be made. The turning of the machine is assisted by shifting the vertical rudder 59.

The stabilizing plane 30 is used in ascending and descending and when performing this function it is assisted by the horizontal rudder 57 the plane 30 being shifted by the sheave 33 as previously described. The plane is shifted laterally by the sheave 34 to correct minor disturbances of the equilibrium of the machine at such times when the warping of the main planes does not become necessary.

Obviously variations and modifications of the structure of the machine may be made without departing from the spirit of the invention or the scope of the claims.

I claim:

1. In a flying machine, the combination of a mast, a longitudinal horizontal beam, a transverse horizontal beam, a main plane disposed on the transverse horizontal beam, an auxiliary plane spaced from and parallel to the main plane, means for bracing the mast, beams and planes end to end, and means for simultaneously warping the main and auxiliary planes.

2. In a flying machine, a main vertical mast, a longitudinal horizontal beam, a transverse horizontal beam, a main plane disposed on the transverse horizontal beam, an auxiliary plane disposed below the main plane and parallel therewith, means for bracing the mast and beams end to end, means for warping corresponding edges of the coincident planes simultaneously, and means for propelling the machine through the air.

3. In a flying machine, a main vertical mast, a longitudinal horizontal beam, a transverse horizontal beam, a main plane disposed on the transverse horizontal beam, an auxiliary plane disposed below the main

plane and parallel therewith, a stabilizing plane mounted on the vertical mast and located above the main plane, a rectifying plane mounted on the main mast and located above the stabilizing plane, means for warping corresponding edges of the superimposed main and auxiliary planes simultaneously, means for shifting the stabilizing plane, means for bracing the mast and beams end to end, and means for propelling the machine through the air.

4. In a flying machine, a main vertical mast, a longitudinal horizontal beam, a transverse horizontal beam, brace wires connected between the extreme ends of the respective mast and beams one with another, a main supporting plane disposed on the transverse beam, horizontal and vertical rudders located at the rear end of the longitudinal beam, a landing skid adjacent the rudders, ground wheels at the lower end of the vertical mast, means for warping the front edges of the main plane and means for turning the rudders on their pivots.

5. In a flying machine, the combination with the frame; of a longitudinal horizontal beam, a vertical and a horizontal rudder movably mounted on the rear end of the beam, crank arms coöperating with each rudder, a shaft located in the body of the machine, treadles movably mounted on the shaft said treadles being movable independently of each other, an arm coöperating with each treadle, and cables connected between the ends of the treadle arms with the respective ends of the rudder arms.

6. In a flying machine, a main vertical mast, a longitudinal horizontal beam, a transverse horizontal beam, brace wires connected between the extreme ends of the mast and beams one with the other, a main supporting plane disposed on the transverse beam, an auxiliary supporting plane located below the main plane and having support on certain of the brace wires, movable arms located adjacent the seat of the aviator, a cable connected at one end to each of the arms and at its other end to the front edges of the superimposed main and auxiliary planes one of said cables being connected at one side while the other is connected at the opposite side, said cables being guided by pulleys, and means for returning the planes after flexure.

7. In a flying machine, a main vertical mast, a longitudinal horizontal beam, a transverse horizontal beam, brace wires connected between the extreme ends of the mast and beams one with the other, a main supporting plane disposed on the transverse beam, an auxiliary supporting plane located below the main plane and having support on certain of the brace wires, movable arms located adjacent the seat of the aviator, a cable connected at one end to each of the arms and

- at its other end to the front edges of the superimposed main and auxiliary planes one of said cables being connected at one side while the other is connected at the opposite side; said cables being guided by pulleys, and means for returning the planes after flexure, said means comprising cables connected between the rear edges of the main and auxiliary planes at both sides and between the main plane and the adjacent wire brace each of said cables having an interposed retractile spring.
8. In a flying machine, the combination with the main vertical mast, and a member mounted on the mast to tilt laterally about a longitudinal axis, of a transverse shaft mounted in the said member to tilt therewith and rotatable about a longitudinal axis, a stabilizing plane supported by the shaft, and independent means for moving the said member and shaft separately to angularly adjust the stabilizing plane longitudinally and laterally.
9. In a flying machine, the combination with a mast and a member mounted on the mast to tilt laterally about a longitudinal axis, of a shaft rotatably mounted in said member and adapted to tilt therewith, a stabilizing plane mounted on said shaft, independent sheaves under control of the operator, and cables passing around such
- sheaves and having connection with the said shafts and stabilizing plane to move each independently, whereby such stabilizing plane may be tilted laterally and longitudinally.
10. In a flying machine, the combination with the main vertical mast; of a universal joint having a traverse circular bore, said joint having circular trunnions at each side for support in corresponding openings in the mast, a shaft rotatably mounted in the bore of the universal joint, said shaft extending at each side, a stabilizing plane disposed on the shaft at each side of the mast, and means for rocking the plane on its lateral and longitudinal bearings.
11. In a flying machine, the combination with the transversely disposed main plane; of a vertical mast and a longitudinal horizontal mast, brace wires connected end to end of the aforesaid masts, a rectifying plane disposed at the top of the vertical mast and having support on the adjacent brace wires, and independently operable means for warping one edge of the main plane when the rectifying plane is deflected by wind pressure.

ALBERT HERBERT SMITH.
